UNITED STATES PATENT OFFICE.

MATT MARKKULA, OF FORT BRAGG, CALIFORNIA.

STAKE FOR CARS.

1,324,402.

Specification of Letters Patent.

Patented Dec. 9, 1919.

Application filed November 11, 1918. Serial No. 261,984.

To all whom it may concern:

Be it known that I, MATT MARKKULA, a citizen of the United States, residing at Fort Bragg, in the county of Mendocino and State of California, have invented certain new and useful Improvements in Stakes for Cars, of which the following is a specification.

My invention relates to stakes for flat cars and has particular reference to such devices adapted to retain logs, spars, or the like in place upon the car.

An important object of the invention is to provide means whereby the stake or stakes upon one side of the car, may be released by the operator, standing near or upon the opposite side of the car, whereby the operator is not subjected to the danger of the logs or the like rolling from the car.

20 A further object of the invention is to provide an apparatus of the above mentioned character which is adjustable for the reception of loads of different sizes, and which is of simplified construction 25 and easy to operate.

Other objects and advantages of the invention will be apparent during the course of the following description.

In the accompanying drawings forming a part of this specification and in which like numerals are employed to designate like parts throughout the same,

Figure 1 is a plan view of apparatus embodying my invention.

35 Fig. 2 is a longitudinal sectional view taken on line 2-2 of Fig. 1,

Fig. 3 is an end elevation of the apparatus, with the latch plate in the lowered position, and,

40 Fig. 4 is a similar view with the latch plate raised.

In the drawings, wherein for the purpose of illustration is shown a preferred embodiment of my invention, the numeral 45 5 designates the side sills of the ordinary flat car. Arranged upon and secured to these side sills, preferably near each end thereof, is a pair of transverse bolsters 6, which may be in the form of beams. These 50 bolsters are spaced, providing a passage 7, as clearly indicated in Fig. 1.

Arranged between the bolsters 6 are vertically swinging stakes 8. Each stake is

provided at its lower end with an opening 55 for the reception of a pivot element or pin 9, adapted for insertion within a selected pair of spaced openings 10. It is thus apparent that the stake 8 is pivotally connected with and between the bolsters 6 and is adapted to be longitudinally adjusted 60 with relation to the bolsters, for receiving therebetween loads of different size.

The stake 8 near or upon one side of the car has connection near its upper end, as shown at 11, with a flexible element or 65 chain 12, which extends to or upon the opposite side of the car. Each chain 12 extends through an opening 13, in a base-plate 14, vertically arranged, and secured to the sill 5, adjacent the ends of the bolsters 6. 70 The chains 12 cross each other and extend in opposite directions, as clearly shown in Fig. 2. Pivoted to the base-plate 14, as shown at 15, is a latch 16, having an opening or notch 17, adapted to receive the vertical links of the chain, but preventing the passage of the horizontal links therethrough. It is thus seen that when the latch 16 is swung downwardly, as shown in Fig. 75 3, its notch 7 will receive a vertical link of 80 the chain 12, thereby positively locking the chain against longitudinal movement. The free end of the latch 16 is bent outwardly to provide an extension 18, which may be struck by a hammer or the like to move the 85 latch 16 to the open or closed position.

With the stakes 8 in the raised position, as indicated in Fig. 2, it is obvious that they will retain the load upon the car. To unload the car, the operator stands upon one 90 side of the car opposite the side upon which the logs or the like are to be discharged from the car. The operator strikes the extension 18 with a hammer or the like, forcing the latch 16 upwardly out of engagement with the chain 12. The stake 8 upon the unloading side of the car is then free to drop to a more or less horizontal position, between the bolsters 6, and the logs or the like are free to roll from the unloading side 100 of the car.

It is to be understood that the form of my invention herewith shown and described is to be taken as a preferred example of the same, and that various changes in the 105 shape, size, and arrangement of parts may

be resorted to without departing from the spirit of the invention or the scope of the subjoined claim.

Having thus described my invention, I
5 claim:

In apparatus of the character described, the combination with a flat car, of a pair of bolsters arranged upon and secured to the flat car and extending transversely
10 thereof in spaced relation to provide a recess therebetween, said bolsters being provided near each end with a plurality of spaced pairs of openings, vertically swinging stakes arranged within the recess between the bolsters near their ends, pivot elements connected with the lower ends of the stakes and adapted to be inserted within selected pairs of transverse openings in the bolsters so that the stakes may be adjusted
15

toward and away from each other longitudinally of the bolsters, chains secured to the stakes near their upper ends and extending to the opposite sides of the car, said chains consisting of horizontal and vertical links, base-plates secured to the sides of the car and having suitably shaped openings for receiving the chains so that the vertical and horizontal links may pass freely therethrough, and latches pivoted to the base-plates upon one side of the chains and having transverse openings formed therein to receive the vertical links of the chains.

In testimony whereof I affix my signature in presence of two witnesses,

MATT MARKKULA.

Witnesses:

J. A. PETTES,
LENORA E. CLARK.
